APPARATUS FOR DISTILLING CRUDE OIL
AND OTHER LIQUIDS

George W. T. Beck, Cody, Wyo.

Application February 9, 1932, Serial No. 591,895

4 Claims. (Cl. 196—132)

This invention relates to apparatus primarily intended for use in a continuous process for distilling crude oil and separating, from the heavy body of the oil, its lighter derivatives, such as gasoline, kerosene, and the like.

It is, of course, well-known that by a process of distillation the lighter volatile ingredients of crude oil may be separated from its heavier components such as tar, pitch, and asphalt, and many types of apparatus for carrying out this process have been heretofore designed or suggested. It is also well-known that the lighter volatiles contained in crude oil make their escape in the form of a vapor when the temperature is raised only a relatively small amount and that thereafter slight increases in temperature result in the successive boiling out of vapors having different characteristics and flash points.

In processes now commercially practiced, it is attempted in certain instances, by passing the crude oil through a series of retorts heated to different temperatures, to first remove the ingredients of the oil which, taken together, comprise commercial gasoline, then to remove vapors which, when condensed, comprise commercial kerosene, and so on. It is essential in such processes to have at all times accurate control of the temperatures to which the oil is raised at various points in its travel through the apparatus, but difficulties have been heretofore met with in attempting to secure accurate temperature control.

It is an object of the present invention, therefore, to provide an apparatus which may be utilized in the continuous treatment of crude oil for the recovery of commercially salable products, in which means is provided whereby the most precise temperature control may be realized. It is a further object of the invention to provide an apparatus for the continuous treatment of crude oil which is of extreme simplicity, may be erected at small expense, may be easily and cheaply operated, and is of such nature as not to require the attention of highly skilled attendants.

The invention contemplates an entirely efficient distilling apparatus of this class which may be easily erected and operated at points remote from industrial centers, for instance, actually in the fields where the oil is produced, the apparatus constituting a simple distilling apparatus as distinguished from the large, complicated, and very expensive oil cracking plants which are now in widespread use near the larger cities.

In the accompanying drawing, one form of the invention is disclosed by way of example, but it will be appreciated by one skilled in the art that

the design and arrangement of the various elements of the invention may be considerably modified in adapting the principles of the invention to varying circumstances.

In the drawing:

Figure 1 is a vertical axial sectional view through one distilling unit of the improved apparatus;

Fig. 2 is a section on line 2—2 of Figure 1;

Figure 3 is a transverse section through the distilling unit, to a somewhat larger scale; and

Figure 4 is a section on line 4—4 of Figure 3.

The distilling unit illustrated by way of example comprises essentially an elongated slightly inclined chamber through which the oil is intended to flow and from which the vaporous distillate may be conveniently removed for subsequent condensation. In the construction of the floor, walls, and top of the chamber, metallic plates may be conveniently used, and for heating the chamber any suitable combustible may be burned or electricity employed if it can be cheaply obtained in large quantities. The floor or bottom 10 of the distilling unit illustrated comprises essentially a plurality of rectangular superposed metallic plates, any desired number of these plates being used and the plates being fabricated of steel and copper. A copper plate is interposed between each two steel plates, and all of the plates are suitably secured together as, for instance, by bolts 11, so that the surfaces of adjacent plates are very nearly, if not quite, in full bearing. The side walls 12 and top 13 may be of steel, and likewise the walls of the oil supply reservoir 14 may be formed of the same or similar material.

The unit is supported by four vertically adjustable legs 15, the upper ends of which are rotatably received within retaining devices 16 secured to the under surfaces of supporting cross beams 17, the lower ends of these vertical supporting legs 15 being threaded and the threads thereof engaging in interiorly threaded sleeves 18 supported upon any suitable base or foundation 19. Each of the adjustable supporting rods is provided with a handle 20, by means of which it may be rotated and caused to move upwardly or downwardly relatively to its associated supporting sleeve. By adjusting the supporting legs 15, therefore, the floor of the chamber may be caused to have any desired inclination to the horizontal so that oil introduced into the chamber at one end would readily flow over the bottom and longitudinally of the chamber to the other end.

The oil supply tank 14 is located at one end of the distilling chamber, and oil is supplied to this

tank through a supply pipe 22 which may be controlled by a hand valve 23, the flow of crude oil into the tank being also controlled by a valve 24 manipulated in its opening and closing movements in accordance with the rising and falling movements of float 25 which is connected to the valve by any suitable system of links and levers. The level of the oil in the chamber or tank 14 is, therefore, maintained at any desired height above the floor, for instance, as shown in the drawing. The substantially vertically disposed plate which comprises the dividing partition between the oil tank 14 and the distilling chamber terminates just above the floor or bottom of the unit, leaving a horizontally disposed, elongated, and narrow slot-like aperture 26 through which oil may continuously pass from the tank 14 into the upper end of the distilling chamber. Oil thus introduced under the desired static head will flow by gravity from its point of introduction to the lower end of the chamber where it falls into a well or trap 27 provided with a baffle 28, the oil standing in this trap constituting a liquid seal for the vapors generated in the distilling chamber while the trap does not prevent the outflow of oil from the chamber to a point of discharge such as indicated at 30. Preferably the oil passing through the unit illustrated, and discharged therefrom, will pass immediately into a second unit of similar design, as will be hereinafter more fully explained.

In its passage from one end of the chamber to the other, the oil is subjected to a heating operation, heat being applied to the bottom plate 10 and this plate raised to any desired temperature. The heat may be generated in various ways, but where gas is available, which is usually the case, the heating means may conveniently be a gas burner positioned beneath the floor of the chamber. A gas supply pipe, for instance, is indicated at 31 and three gas burner units at 32, 33, and 34, respectively, these units being connected to the gas main 31 by branch pipes 32', 33', and 34'. Positioned in each branch pipe is a valve V for controlling the flow of gas from the supply pipe 31 to the associated gas burner, and each of these valves V is automatically controlled to regulate the gas flow thereby by means now to be described. The three control means are identical in construction, and the specific details of one only need therefore be set forth.

Referring particularly to Figure 3, it will be observed that extending vertically downwardly from the top to the bottom of the distilling chamber is a tube 35, the upper edge of this tube being sealed to the top of the chamber and the lower edge to the bottom. Positioned within tube 35 is a second tubular member 36 of copper having an enlarged lower end portion 37. This enlarged lower end portion 37 is filled with mercury, or similar fluid, and upon the upper level of the body of mercury thus enclosed rests the lower face of a piston 38 which closely fits against the inner wall of tube 36. To facilitate introduction of the piston 38 into tube 36, it is provided with an air duct 39 extending from top to bottom so that the air trapped below the piston and above the body of mercury may make its free escape as the piston is lowered. Upon the bottom of the piston, and forming the effective face thereof, is a rotatable disc 40 held in position by the lower end of the central rod 41, and which disc has an eccentric aperture 42 which may be brought into or out of register with the duct 39 in the piston, as desired. In lowering the piston, duct 39 and aperture 42 are in register, and after the piston

is positioned, disc 40 may be rotated so that aperture 42 and duct 39 are out of register, as shown in Figure 4, the disc then being clamped in such position by any suitable means, such, for instance, as by lock nuts 43 threaded on the rod 41 above the upper end of the piston.

Rod 41 is continued upwardly beyond tube 36 and has a flattened portion at its upper end provided with a series of apertures therein, such, for instance, as shown at 44. Through any one of these apertures, as desired, is passed a cotter pin or the like 45, which pin also passes through an aperture formed in the adjacent end of a lever 46 pivotally supported at 47 on the top plate of the distilling chamber. A compression spring 48 positioned to the opposite side of the fulcrum point 47 of the lever carries the weight of the lever and also tends to maintain piston 38 in close contact with the upper surface of the body of mercury. Lever 46 projects from the side of the distilling chamber, and to its outer end is pivotally secured the upper end of a vertically disposed link 49. Link 49 has its lower end pivotally connected to a crank 50 fixed on one end of a rod 51, the opposite end of which rod is connected to valve V.

By the arrangement of parts just described, it is clear that the valves will be manipulated in accordance with changes in volume of the body of mercury in the mercury container 37. Expansion or contraction of the mercury body also is caused by increase or decrease in temperature of the bottom plate 10 of the distilling chamber. Hence it follows that, by the means just described, this bottom plate may be maintained accurately at any desired temperature, increase in temperature thereof above the desired limit causing expansion of the mercury, which in turn results in cutting off of the gas flow to the heating unit, and decrease in temperature of the bottom plate resulting in increase of flow of the heating gas.

Three identical heat control units of the type just described are provided along the length of the chamber, but a larger or smaller number of these units may be used as desired, the number selected being dependent somewhat upon the length of the chamber and the temperature of the oil which is freshly supplied in a continuous manner to the chamber at its upper end. It is intended, of course, that the oil shall be rapidly heated as it flows in a thin film along the bottom of the chamber but shall at no time be heated above a predetermined temperature. To obtain rapid heating, the right-hand or uppermost heating unit may have a hotter flame than the others without imparting too high a temperature to the oil, and the intermediate heating unit may be so regulated that that portion of bottom plate 10 which lies above it may be hotter than the left-hand end of the plate can be allowed to be heated. This follows from the fact that the oil increases in temperature as it flows through the chamber and is, of course, quite cool as it enters.

The vaporous distillate may be conducted away, for instance, through a conduit 53 and condensed by any suitable condensing mechanism, which it is not necessary to illustrate. As has been before stated, a number of units such as shown in the drawing are preferably provided, the second unit receiving the oil which passes through the first, and so on with subsequent units. By providing a battery of units, therefore, arranged to work at different temperatures, the whole series of distilling operations may be successively conducted and the crude oil originally introduced into the

first unit practically entirely separated from all of its lighter ingredients, only pitch, tar, and asphaltic compositions remaining.

While the apparatus just described is particularly suited for the distillation of crude oil, it will be apparent that it may be employed without substantial change in the distillation of other products. Also, where high temperatures must necessarily be employed, it may be necessary to replace the mercury-type thermostat with one which will function more accurately at such temperatures. Again, for certain operations, different types of distilling chamber bottoms may be substituted for that disclosed. A great advantage of the copper-steel plate bottom, however, resides in its ability to quickly and evenly distribute the heat applied so that the upper surface of the bottom, over any one transverse strip, has the same temperature, the copper plates effecting the immediate transfer of heat laterally due to the great heat conductivity of copper.

Having thus described the invention, what is claimed as new and desired to be secured by Letters Patent is:—

- 25 1. An oil distilling apparatus comprising an elongated chamber having a flat bottom inclined to the horizontal over which oil may pass in a thin sheet, and means for heating said chamber from below, said means including a plurality of gas burners together with mechanism for controlling the action of each in accordance with the temperature of the chamber bottom lying immediately above the same.
- 30 2. In an oil distilling apparatus, in combination, a distilling chamber having a slightly inclined flat floor or bottom, means for discharging

oil onto said bottom at the upper end thereof in a substantially horizontal direction and under substantially uniform pressure, and means for heating said bottom to the desired temperature, said last mentioned means including a gas burner beneath the bottom, a valve controlled conduit leading to said burner, and a thermostat responsive to the temperature of the bottom and connected to the valve for automatically controlling the position of the valve in accordance with the temperature of the bottom. 80

3. In an oil distilling apparatus, in combination, a distilling chamber having a flat floor or bottom slightly inclined to the horizontal, means for discharging oil in a wide thin stream onto the bottom at its upper end, and means for heating the bottom to the desired temperature, said last mentioned means including a gas burner beneath the bottom, a valve controlled conduit leading to said burner, a thermostat comprising a receptacle for expansible fluid mounted directly on the bottom, and a piston fitting within said receptacle and resting directly upon the surface of the fluid contained therein, said piston being connected to the gas control valve. 90

4. An oil distilling apparatus comprising an elongated chamber having a flat inclined bottom, said bottom being composed of a plurality of copper plates and a plurality of steel plates, the copper plates alternating with the steel plates and all of said plates being secured together so as to form a compact, sectionally continuous, composite unit, and means for heating said bottom from beneath the same. 105
